UNITED STATES PATENT OFFICE.

FITCH H. BEACH, OF CHARLOTTE, MICHIGAN.

COMBINED BRIDGE-FLOOR.

1,385,421.

Specification of Letters Patent. Patented July 26, 1921.

Application filed December 26, 1919. Serial No. 347,310.

To all whom it may concern:

Be it known that I, FITCH H. BEACH, a citizen of the United States, residing at Charlotte, in the county of Eaton and State 5 of Michigan, have invented a new and useful Combined Bridge-Floor, of which the following is a specification.

This invention relates to new and useful improvements in flooring construction, and 10 more particularly to a flooring construction to be employed in connection with highway bridges.

The primary object of the invention is to provide an auxiliary flooring adapted for 15 use in connection with light bridge construction and one which will be capable of supporting concrete, or asphalt, usually employed in road construction.

A further object of the invention is to 20 provide means of this character which will support the asphalt, and which means insures against the concrete or asphalt working through between the elements of the support, and absolutely prevents creeping of the 25 asphalt along the flooring of the bridge.

A still further object of the invention is to 30 provide a flooring made up of a plurality of sections to be laid on the usual bridges, thus eliminating the necessity of building 35 an entire new structure and consequently reducing the length of time that the bridge is closed to traffic, to a minimum.

With the foregoing and other objects in view which will appear as the description 35 proceeds, the invention resides in the combination and arrangement of parts and in the details of construction hereinafter described and claimed, it being understood that changes in the precise embodiment of the 40 invention herein disclosed, may be made within the scope of what is claimed, without departing from the spirit of the invention.

Referring to the drawings:—

Figure 1 illustrates an end elevational 45 view of one of the bridge sections, the same being shown as applied to the bridge structure.

Fig. 2 illustrates a sectional view through adjacent sections, and

Fig. 3 illustrates a fragmental plan view 50 of abutting ends of sections.

Referring to the drawing in detail, the reference character 5 designates one of the transverse floor beams, employed in the 55 usual bridge construction, a bridge being formed of a plurality of such floor beams,

supported in spaced relation with each other, and retained in such position by the standards 6, or other suitable elements, according to the type of bridge. 60

Extending longitudinally of the bridge, and supported on the floor beams 5, are the transversely spaced I beams 7, the lower portions thereof being shown as resting on the upper surfaces of the floor beams 5, the 65 upper surface of each of the I beams 7 supporting the base, or floor support 8.

This base 8, is formed of a plurality of boards 9 and 10 extending transversely of the bridge, and disposed on the I beams 7, 70 edgewise, or in a position so that the opposed side faces of adjacent boards, will contact with each other, the boards 10 forming a part of the base 8 being wider than the boards 9 thereof, so that when the boards 75 are arranged in operative position, recessed portions 11 will be formed throughout the width of the bridge to which the same is applied.

The boards 9 and 10, forming the base 8 80 are secured together by means of the relatively long bolts 12, which pass through registering openings in the boards 9 and 10, and secured therein by means of the nuts 13 operating on the threaded ends of the 85 bolts 12.

In the construction of the bridge, the flooring is preferably formed of a plurality of sections of equal widths, the sections being provided with a block 14, which as 90 shown, is spaced from the lower edge of the section and a block 15, which has its lower edge in alinement with the lower edge of the base 8, so that an overlapping joint is provided at the adjacent edges of sections, 95 so that the covering, supported by the base 8, and to be hereinafter more fully described, will not work through between adjacent sections.

Each of the sections, is also provided with 100 spaced steel plates 16 secured along one of the sides thereof, and each of these plates is provided with a cut out portion 17 to embrace the respective I beams 7, so that lateral movement of the sections with relation 105 to the frame of the bridge construction will be absolutely prevented, but at the same time these plates 16, support the sections in suitable spaced relation with each other, to permit of movement of one section with relation to the other, to compensate for expansion and contraction of the flooring, due 110

to heat and cold. Staples or bolts 18, are provided for securing the plates 16 to the sections, so that the same will move with the bridge sections.

5 Securing staples 19, straddle the connection between adjacent sections, the staples including depending arms 20, which are embedded in the surfaces of opposed sections, and as shown, the staples are arranged at 10 angles with relation to each other, so that the securing qualities thereof are greatly increased.

A flooring constructed of a plurality of sections as shown, presents a surface including a plurality of spaced recesses for supporting the asphalt, concrete, tar, or other road dressings employed in road construction, the dressing, finding its way between the extended ends of the boards 10, thus 20 anchoring itself to the flooring or base 8.

Longitudinally extending guard strips 21, are disposed adjacent the side edges of the flooring or base 8, and prevents lateral movement of the flooring or dressing, with rela-

tion to the base and frame work of the 25 bridge, drain openings 22 being provided in the flooring, to carry off the water, before the same contacts with the guard strips 21.

Having thus described the invention, what is claimed is:—

30 In combination with a bridge construction including transverse floor beams, I beams supported by the floor beams and disposed in parallel relation, sectional flooring, steel plates carried by the sectional flooring, each 35 steel plate having a cut out portion adapted to embrace a portion of the I beam associated therewith, and each of said sections having a recessed upper surface to accommodate a surfacing material.

40 In testimony that I claim the foregoing as my own, I have hereto affixed my signature in the presence of two witnesses.

FITCH H. BEACH.
